GOLF BALL RETRIEVER

Anthony T. Zagwyn, Delavan, Wis., assignor to A J Industries Corporation, Delavan, Wis., a corporation of Wisconsin

Filed Apr. 28, 1965, Ser. No. 451,494
5 Claims. (Cl. 294—19)

The present invention relates to golf ball retrieving devices and more particularly to a lightweight golf ball retriever.

It is an object of the invention to provide a lightweight and compact golf ball retriever particularly suitable for carrying and employment by an individual golfer.

It is a further object of the invention to provide a golf ball retrieving device for easily retrieving a golf ball from water, ground obstacles, traps, or other difficult locations, which golf ball retriever is lightweight and compact yet has sufficient extension and strength to extract the golf ball from such locations.

It is a more specific object of the invention to provide a low cost golf ball retrieving device which may be compactly stored, yet readily extends and opens into a high strength ball netting basket configuration particularly suited for removing an individual golf ball from water, mud, weeds or other obstructing materials.

The above and other objects and advantages of the present invention will become apparent from the following detailed description when considered in conjunction with the accompanying drawings wherein:

FIGURE 1 is a perspective view of an exemplary golf ball retriever embodying the features of the present invention;

FIGURE 2 is a side view of the golf ball retriever of FIGURE 1;

FIGURE 3 is a frontal view of the golf ball retriever of FIGURES 1 and 2 in its storage or folded position;

FIGURE 4 is a partial cross sectional view taken along the line 4—4 of FIGURE 2;

FIGURE 5 is a partial cross sectional view taken along the line 5—5 in FIGURE 4.

The golf ball retriever comprises basically an annular member slightly larger in diameter than a golf ball secured to an elongate telescoping handle, which annular member has a plurality of elongate arcuate retaining means secured thereto. The retaining means are preferably rotatable into alignment with the annular member for compact storage, and rotatable into a basket configuration with said annular member to provide a high strength lightweight golf ball retriever.

Referring now to the drawings, and particularly to FIGURE 1, the exemplary golf ball retriever illustrated therein is indicated generally by the reference number 10. An annular band 12 is secured to one end of an elongate telescoping handle 14 and has a first bail member 15 and a second bail member 16, each rotatably mounted between opposite sides of the band.

Referring specifically to the band 12, this band preferably provides the primary structural member for the golf ball capturing portion of the ball retriever 10 and also defines the aperture 18 or open mouth of the retriever. This aperture 18 is preferably slightly larger in diameter than an individual standard golf ball. The band 12 is preferably constructed from a thin strip or ribbon of stainless steel, aluminum or other suitable material bent into a closed circle to form a thin cylindrical band.

It will be observed from FIGURE 3 that only the thin edge of the band is presented axially thereof, while the width of the band, which is substantially greater than its thickness, extends axially of the band. Thereby the band 12 presents maximum strength and minimum profile in its

2

axial direction, in which direction it presents its mouth and is moved in retrieving a ball.

The band 12 is preferably mounted securely to the end of the elongate handle 14 by an integral extension 20 of the band 12. As illustrated in FIGURE 3, a preferred construction of the extension 20 is to position the two ends of the strap forming the band together in parallel contact and in radial extension from the band. The end of the handle 14 then preferably encloses and secures together this integral extension.

To provide mounting for the bails 15 and 16, the band 12 preferably has four small apertures 22 therethrough evenly spaced around the band. Thus each aperture 22 is diametrically opposite another aperture 22 at the opposite side of the band. The apertures 22 are preferably located so that the integral extension 20 is spaced from any one of them.

Turning now to the two substantially identical bails 15 and 16, they are preferably lightweight unitary and semi-circular resilient members. When the bails are unfolded they mutually form an effective ball retrieving net or mesh basket in combination with the band 12, which provides the rim and support therefor. The two bails are preferably mounted radially disoriented from one another by approximately 90 degrees so that in the unfolded upright or bail position they are at right angles to one another. When each bail is rotated into the bail position it is preferably at the maximum extension from the band, and at right angles thereto.

The preferred manner of fastening of each bail to the band is by pivotally mounting the ends of each bail through diametrically opposite apertures 22. Thus each bail extends arcuately across the band 12 between opposing sides. Any suitable pivotal securing means may be employed. In the configuration disclosed the ends of the bails are deformed into smooth retaining portions, so that the bail is freely rotatable with respect to the band yet secured therefrom.

The compact foldability of the retrieving device is provided by a bail configuration which allows each bail to be rotated into flush alignment with the band 12, closely spaced from the band's surface. In the configuration shown each bail folds into a position around one-half of the outside surface of the band. Accordingly the preferred shape and dimensions of each bail are substantially the same as the exterior of the band.

It will be noted that the cylindrical exterior surface of the band 12 is preferably chordal to the surface of revolution of each bail. This factor is preferably employed to retain the band in the folded position. The size of each bail is preferably such that the edges of the band interfere with the rotation thereof and provide resistance to forcing the bail over the edge of the band. The bail is preferably sufficiently slightly larger in circumference than the band so that it will pass the edge of the bail but only with the application of some external force.

Each of the bails 15 and 16 is preferably elongate, providing a small cross sectional area in relation to its length. This provides a minimum profile for substantially unobstructed movement of the net formed by the bails through mud, water, gravel or other materials. Thus there is a minimum resistance to the retrieving movements of the retriever through such material.

The preferred material for the bails is round metal wire of stainless steel, aluminum or other suitable material. A high strength material is preferred as it allows a small diameter or cross sectional area and therefor a minimum profile.

To maintain the bails 15 and 16 in the bail position the golf ball retriever 10 may provide detention means. A preferred detention means is provided by constructing

and mounting the bails as shown so that they mutually resiliently engage one another in the bail position. That is, the bails springedly abut one another.

Additional detention may be provided by suitable means such as the illustrated detents 24 and 26 at the midpoints of the bails. As particularly shown in FIGURES 4 and 5, a detent or notch 24 on the bail 15 engages in a detent 26 on the bail 16, allowing the bails to interlock. The flexibility and resiliency of the bails allow them to be moved in or out of this interlocked engagement without substantial force.

Turning to the preferred handle 14, this is a three section telescoping tubular aluminum handle. It is extendable to a substantial length for retrieving golf balls from various obstacles. The tubular telescoping construction allows the handle 14 to be carried directly in a golf bag since it has a relatively small diameter and a retracted length comparable to a golf club shaft. Preferably the smallest diameter section is connected to the band 12.

A preferred arrangement for securing the handle 14 to the band 12 is to partially flatten or crimp the end portion 28 of the end-most tubular section of the handle so that it forms an aperture therein corresponding generally in shape to the integral extension 20 from the band. This flattened portion 28 may then be tightly mounted over the integral extension 20. Further retention is preferably provided by a conventional rivet or other suitable fastening means.

The operation of the golf ball retriever 10 is simple, convenient and effective. The handle 14 may first be extended to the length most suitable for retrieving the ball from the particular obstacle. The bails 15 and 16 will normally be in their compact storage position with each bail in flush alignment with the band 12. To form the retriever configuration each bail is rotated out of alignment with the band 12 into the bail position. The two bails resiliently engage one another and are thereby self-retained or interlocked in the upright bail position, additionally secured by the mating detents 24 and 26. Holding the handle 14 the golfer then "fishes" or "nets" for the golf ball, moving the open mouth or aperture 18 of the retriever toward the ball. The ball passes through the band 12 and is retained or netted in the open mesh basket defined by the bails.

A principal advantage of the retriever 10, in addition to its lightweight portability and compact folding storage, is its retrieving operation in mud, weeds and other obstructions. The previously described construction of the band 12 provides a very thin or knife edge profile to the movement of the band through the obstructing material. Similarly the bails offer a minimum area and resistance. Accordingly the retriever can be easily forced through such material to net the ball, and the width of the band provides sufficient strength and rigidity to withstand the resistance that is encountered. Further, since the bails are each suspended concavely from the band with respect to the movement of the retriever, the material forced through the retriever places only non-deflective tension forces upon the bails. The retriever is not clogged or obstructed in such "fishing" operations since the large open mesh configuration preferably provided by only two bails allows any materials significantly smaller than the golf ball to freely pass between the bails, and any material significantly larger than the golf ball will not pass through the band.

It may be seen that there has been disclosed herein a novel golf ball retriever having a low cost, lightweight construction and compact portability together with an efficient high strength ball retrieving action. Numerous modifications and variations of ball retrievers in accord-

ance with the invention will be apparent to one skilled in the art, and it is intended to encompass in the following claims all such variations and modifications as fall within the true spirit and scope of the invention.

5 What is claimed is:

1. A retrieving device for a golf ball, said retrieving device comprising: an elongate telescoping handle; a thin cylindrical band secured to one end of said handle, said band providing an opening therethrough somewhat larger than said golf ball; a pair of elongate semi-circular bails independently rotatably secured to said band at right angles to one another, the ends of each bail being secured at diametrically opposite positions on said band, said bails being rotatable into flush alignment with said band and rotatable out of alignment with said band to define a golf ball retaining mesh basket.

10 2. A retrieving device for a golf ball, said retrieving device comprising: an elongate telescoping handle; a thin cylindrical tubular band secured to one end of said handle, said band providing an opening therethrough somewhat larger than said golf ball; a pair of elongate semi-circular resilient bails independently rotatably secured to said band at right angles to one another, the ends of each bail being secured at diametrically opposite positions on said band, said bails each being rotatable into flush alignment with said band and rotatable out of alignment with said band into a position at right angles thereto and in resilient engagement with one another to define a golf ball retaining mesh basket.

15 3. A retrieving device for an individual golf ball, said retrieving device comprising: a thin cylindrical tubular band secured to one end of said handle, said band providing an opening therethrough somewhat larger than said golf ball; a pair of similar elongate semi-circular resilient bails independently rotatably secured to said band at right angles to one another, the ends of each bail being secured at diametrically opposite positions on said band, said bails being rotatable into flush alignment with said band and rotatable into a bail position at right angles to said band resiliently engaging one another and defining a golf ball retaining mesh basket; detention means acting on said bails to secure said bails in said bail position; an elongate telescoping handle; and an extension from said band spaced from said bails mounting said band to said handle.

20 4. The retrieving device of claim 3 wherein said detention means comprises central detents on said bails resiliently securing said bails to one another.

25 5. A retrieving device for a golf ball, said retrieving device comprising: an elongate telescoping handle; a cylindrical band secured to one end of said handle, said band providing an opening therethrough somewhat larger than a golf ball; and at least a pair of elongate and generally semicircular bails, said bails having opposing ends rotatably secured to opposing sides of said band, said bails being radially spaced on said band intersecting one another, and said bails being rotatable only about their said opposing ends into alignment with said band and rotatable out of alignment with said band to define a golf ball retaining mesh basket.
